UNITED STATES PATENT OFFICE.

EDWARD SAALBACH, OF WASHINGTON, DISTRICT OF COLUMBIA.

DESIGN FOR A BOX.

SPECIFICATION forming part of Design No. 24,452, dated July 2, 1895.

Application filed May 31, 1895. Serial No. 551,330. Term of patent 3½ years.

To all whom it may concern:

Be it known that I, EDWARD SAALBACH, a citizen of the United States, residing at Washington, in the District of Columbia, have invented a new and original Design for a Box, of which the following is a specification.

This invention relates to a new and original design for boxes used for advertising purposes or as a toy, and it has for its object to provide a design of this character that shall be both useful and ornamental.

The leading feature of the design resides in a box resembling in general appearance a steam man-of-war, and having an elliptically-shaped body tapered at one end into a point and provided with a straight horizontal bottom portion and perpendicular ends disposed at right angles to said horizontal bottom portion, and an elliptically-shaped lid or cover 20 tapered at one end into a point and bounded at its edge by a continuous rounded peripheral projection.

In the drawings, Figure 1 is a perspective view of a box embodying the herein-described design. Fig. 2 is a side elevation thereof. Fig. 3 is a vertical transverse sectional view.

Referring to the drawings, the numeral 1 designates a box-body that is substantially of an elongated elliptical shape and is tapered at one end, as at 2, into a point. The 30 elliptically-shaped body 1 is provided with a straight horizontal bottom portion 3 and perpendicular ends 4, that are disposed at right angles to said horizontal bottom portion 3. The box-lid 5, that fits over the box-body 1, is also elliptically shaped and is tapered at one end to a point, as at 6. The 35 said elliptically-shaped lid 5 is bounded at its edge by a continuous rounded peripheral projection 7.

What I claim is—

The design for a box herein shown and described.

In testimony that I claim the foregoing as my own I have hereto affixed my signature in 45 the presence of two witnesses.

EDWARD SAALBACH.
